UNITED STATES PATENT OFFICE.

SAMUEL M. KINTNER, OF PITTSBURGH, PENNSYLVANIA, ASSIGNOR TO WESTINGHOUSE ELECTRIC & MANUFACTURING COMPANY, A CORPORATION OF PENNSYLVANIA.

TRIODE TUBE.

Application filed July 3, 1926. Serial No. 120,437.

My invention relates to triodes and it has particular relation to devices in which it is desired to make the space between the electrodes as small as is consistent with manufacturing requirements.

In making triode tubes of certain types, in particular, such as are used for radio receiving purposes, it is often important that the tubes shall operate with extremely low power consumption in order to permit operation of such devices from commercially available dry cells, or the like.

In order to obtain a tube complying with such requirements and yet giving sufficient output for operating the ordinary telephones or loud speakers, it has been necessary to design the tube with electrodes of diminutive size which are spaced by distances which would ordinarily be considered as out of question in devices adapted for commercial production.

A tube of the type which has been found best adapted for the conditions outlined above comprises a straight-line filament surrounded by a helical grid and a cylindrical plate and it has been possible to manufacture such tubes with clearances of the order of 35 mils between the individual electrode elements.

Since the grid helix is made of very thin wire, it is necessary to provide a stiffening member for the same in the shape of a grid post disposed lengthwise the helix and welded to the wires thereof. While the grid post does not perform any essential function in the way of controlling the electron discharge from the cathode, it must, nevertheless, be disposed in the very narrow space between the cathode and the anode cylinder and, in view of the practical clearance limitation of about 20 mils between the conducting parts of the electrodes, it was necessary to increase the radius of the plate cylinder by an amount equivalent to the thickness of the grid post, or about 20 mils, in order to make possible the manufacture and operation of such tubes without excessive waste resulting from accidental short circuits between the electrodes. It is clear that the increase of plate diameter which appeared thus to be necessary for the accommodation of the grid post materially detracted from qualities of the tube.

According to my invention, the benefits derived from the extremely small clearance limit between the major portions of the ac-

tive electrode elements are retained, without reducing the clearance in the portions of the interelectrode space in which the grid post is located, by slightly deforming the cylindrical shape of the plate, and, in some cases, 60 of the grid, so that the major portions of the electrode surfaces are spaced from each other by a distance corresponding to the smallest permissible clearance limit.

In the accompanying drawings 65 Figure 1 is an enlarged elevational view of a radio receiving tube embodying my invention, portions of the envelope and the electrodes being broken away,

Fig. 2 is a horizontal sectional view of 70 the electrode assembly in Fig. 1, taken along the line II—II, and

Figs. 3 to 6 are views, similar to Fig. 2, showing modifications of my invention.

My invention will be explained as applied 75 to a radio receiving tube, such as is shown in Figs. 1 and 2 of the drawing, in which a tipless envelope 1 has a reentrant stem 2 which is provided with a flat press 3 in which are fused four lead-in wires 5 to 8 serving 80 to support, and to provide electrical connections to, concentrically arranged cathode, grid and anode members 9, 10 and 11, respectively.

As explained hereinbefore, the tubes of the 85 type under consideration are designed to operate from small-power sources, such as commercially available dry cells, and, accordingly, the electrode structure must be so designed as to give the utmost output at very small 90 power consumption, say, of the order of a quarter of a watt, or less. To this end, the designers make every effort to arrange the cathode filament, grid and anode cylinder as close to each other as possible in order to 95 obtain a maximum amplification factor at a minimum plate impedance.

The electrode assembly illustrated in the drawing presents the utmost limit of development in this direction that has been 100 reached, the controlling limitation in the reduction of the interelectrode spaces being, of course, that the tube shall be suitable for commercial production in large quantities without danger of waste because of short 105 circuits due to small clearances.

The cathode member 9 is made in the shape of a thin, straight-line filament provided with tips 13, the lower tip being welded, or otherwise secured, to an extension from 110

the lead-in wire 5, and the upper tip being welded to a spring 14 held by a carrier rod 15 which is secured to an extension of the lead-in wire 6.

5 The grid member 10 has the shape of a helix of fine wire supported and held in place by a grid post 17 disposed parallel to the filament. The lower end of the grid post is welded or otherwise secured to lead-in wire 10 7, while the upper end thereof is secured to a bracing wire 18 which is held in position by a glass bead 19 fused therearound and around the filament carrier rod 15.

15 The grid helix 10 and the grid-supporting rod 17 are surrounded by the tubular plate member which is supported on a plate carrier rod 21 held, at its lower end, on the plate lead-in wire 8 and, at its upper end, on a bracing rod 22 which is fused into the glass bead 19 20 similar to the grid-bracing rod 18.

25 As shown in Fig. 2, the plate is made by bending a substantially rectangular sheet-metal piece into tubular form and folding side ends of the sheet to form a pair of contacting extensions 25 provided with a longitudinal groove 26 fitting over the plate carrier rod 21.

30 The entire supporting structure is so arranged as to positively locate the cathode, grid and plate with respect to each other as to prevent microphonic noises that may result from even small vibrations caused by shocks or other forces transmitted to the tube. The filament 9 is maintained, at all times, in 35 taut condition by the spring 14 at the upper end thereof.

35 In order to reduce the clearance between the electrodes to a minimum and, at the same time, to provide space for the grid post, the 40 tubular anode or plate 11 is not made of circular shape, as was usual heretofore, but of oval or pear shape, and the grid post is positioned on the side of the tubular plate which bulges outwardly at 27. This shape of the 45 plate and location of the grid makes it possible to keep down the spacing between the outer cylindrical surface of the grid and the 50 cooperating cylindrical portion of the major part of the plate down to the lowest limit required for manufacturing, and other, reasons and, at the same time, to provide the same 55 minimum clearance in the portion of the interelectrode space where the grid post is located. In other words, the major part of the plate 11 is made to conform to the shape of a cylinder having a radius which exceeds the radius of the grid cylinder by the amount of clearance required. However, on the side where the grid post 17 is located, outside the 60 grid helix 10, the plate 11 deviates from the cylindrical shape and is provided with the outward bend 27 increasing at this portion, the width of the plate by an amount corresponding to the width of the grid post 17.

65 The improvement resulting from the fore-

going electrode structure is obvious when it is considered that, for the past several years, it was thought necessary to make the plate in the shape of a cylinder having a radius corresponding to the distance between the filament 9 and the outwardly bent portion 27 of the plate 11; that is, to the sum of the radius of the plate which would be required were there no grid posts to be inserted in the space between the electrodes plus the width of the grid post. Small as the change may appear, it is nevertheless of very great practical consequence since it enables a decrease in the plate impedance, and a proportionate increase of the mutual conductance of the tube by 15 to 20%, as against the prior-art tubes. The beneficial effect is large because of the small magnitude of the clearances, as compared to the width of the grid post under consideration.

70 Thus, in actual tubes made according to my invention, the outer diameter of the grid helix is about 90 mils and the width of the post is about 22 mils. Adding the required clearance of 20 mils to the grid radius of 45 mils 75 we obtain 65 mils as a radius for the major cylindrical part of the grid 11. The distance between the outwardly bent portion 27 and the center of the tubes is then approximately 80 87 mils, corresponding to an increase of about 37% over the spacing of the other portions of the anode from the cathode. Since the plate impedance increases approximately directly 85 with the radius of the plate cylinder, it is clear that a tube with an 87 mil plate radius 90 has a materially larger plate impedance than 95 that of the tube made according to my invention.

100 It is, of course, understood that the precise figures for the electrode dimensions given 105 above are deviated from, to a more or less extent, in the practical construction of the tubes, and are chiefly intended to give a better understanding of the principles underlying the invention and not to limit the scope 110 thereof.

110 The principles underlying the tube construction shown in Figs. 1 and 2, are not restricted to the particular shape or arrangement of the electrodes employed in said tube 115 but may be applied to a wide variety of other electrode constructions. Thus, in the modification shown in Fig. 3, the plate 31 of a shape similar to that shown in Fig. 2, is made so that plate 31 deviates from its cylindrical 120 shape at the place where the two lateral extensions 32 meet to form the plate supporting pin 26, the grid post 17 being located in the widened interelectrode space adjacent thereto.

125 The modification of my invention shown in Fig. 4 distinguishes from those of the previous figures in that the grid is of the oval type, being made in an automatic machine with the grid helix 34 wound around 130

the grid post 17 so that the grid post is disposed in the space between the cathode 9 and the grid helix 34. The shape of the grid helix conforms thus to the principles outlined in connection with the shaping of the plate 11 in Figs. 1 and 2. The major portion of the grid helix conforms to a cylinder having a radius corresponding to the minimum clearance distance from the filament, with the side of the grid helix adjacent to the grid post being bent outwardly by a distance corresponding to the width of the post to provide the same minimum clearance between the inner side of the grid post and the filament. The plate 31 may then have the same shape as that shown in Fig. 3, giving equi-distant spacing between the grid and the plate.

Fig. 5 illustrates the application of the same principles to a grid 10 that is supported on two posts 17 and 37. The tubular plate 38 has, in this case, two outwardly bent portions 39 to provide the additional clearances necessary for accommodating the two posts.

In the constructions hereinbefore described, the cathode was always assumed to be a straight-line filamentary member of small width and, in determining the clearances between the grid and the filament, the width or the shape of the latter appeared to be of little influence. However, the principles underlying my invention are not in any way limited to filamentary cathodes only but may be applied to cathodes of any type. Thus, in the modification shown in Fig. 6, the cathode 41 is made in the shape of a rod member, the outer surface of which constitutes an oval-shape, electron-emitting cathode element 42 which is heated by a pair of internally disposed filamentary heater wires 43, as described in Canadian Patent No. 265,517. To secure the benefits derived from close spacing of the electrodes, the grid 44 is made in the shape of an oval helix which is equi-distant from the oval surface of the cathode member 41. The tubular plate 45 is then made of such shape that the inner surface thereof is spaced from the geometrical body conforming to the outward boundary of the grid helix with the associated grid posts by a distance equal to the minimum inter-electrode clearances. In case of the arrangement shown in Fig. 6, a practically cylindrical plate 45 is thus obtained, the wide spaces between the flat sides of the grid 44 and the adjacent portions of the plate cylinder 45 being used to locate therein two grid-supporting posts 46.

Many other modifications of my invention will suggest themselves to those skilled in the art and it is desired that the scope of the invention shall not be limited except as defined by the appended claims and by the prior art.

65 I claim as my invention:

1. In an electron-discharge tube, a cathode having an electron-emitting outer surface, a tubular electrode surrounding said cathode, a conducting supporting post extending into the space between said cathode and said electrode and filling a substantial part of said space, the adjacent opposite surface portions of said electrodes being so spaced that the free insulating clearances are substantially uniform throughout the entire inter-electrode space.

2. In an electron-discharge tube, a central straight-line cathode member, a tubular electrode enclosing said cathode member and a conducting post extending parallel to said cathode member in the space therebetween, the major portions of the opposing adjacent surfaces of said cathode and said electrode having the same uniform clearance except the portions between which said post is disposed, the clearance at said last-mentioned portions being equal to the clearance between the major portions of the electrodes plus the width of said post.

3. In an electron-discharge tube, a linearly extending cathode member, a tubular grid surrounding said cathode member, a tubular anode surrounding said grid, a post supporting said grid and disposed parallel to the axis thereof, said grid and anode being of such shape and width that the radial insulating clearances between the electrodes are substantially uniform throughout the inter-electrode space.

4. In a hot-cathode-electron-discharge tube, a central linearly extending cathode, a tubular grid helix surrounding said cathode, a tubular plate surrounding said grid helix, a conducting rod extending parallel to said cathode and supporting the turns of the helix in the space between said cathode and said plate, the insulating clearance in a radial direction between the cathode and the plate at the portion where said rod is located being substantially equal to the radial insulating clearance between the other portions of said electrodes, increased by the width of the grid-supporting post to secure minimum insulating clearances between major portions of the electrodes without transgressing the limiting insulating clearance required from reasons of manufacture or operation.

5. In an electron-discharge tube comprising a linearly extending filament, a tubular grid helix surrounding said cathode and a tubular anode surrounding said grid, said electrodes being so shaped and spaced from each other that the distances between adjacent portions of the major parts of the several electrodes shall be as small as is permissible from practical considerations, a grid-supporting post extending into the space between said cathode and said anode and extending parallel thereto, said plate being

bent outwardly to provide additional clearance throughout the portion of the tube accommodating said grid post.

6. In a hot-cathode-electron-discharge tube, a straight-line filamentary cathode, a cylindrical grid concentrically disposed around said cathode, a grid post disposed lengthwise of said grid and supporting the same, a tubular plate surrounding said grid and grid post, the major portion of said plate constituting a cylindrical surface substantially concentric with said cathode and so spaced therefrom as to give substantially the minimum permissible insulating clearance, said plate having an outward lengthwise bend at the portion adjacent to said grid post to accommodate the same while retaining substantially the same insulating clearances as between adjacent portions of the several electrodes at the portions of the electrodes removed from said grid post.

7. In an electron-discharge tube, a substantially straight-line filamentary cathode, a helix of fine wire constituting a substantially cylindrical grid coaxial with said cathode, a tubular anode surrounding said grid, said anode having the shape of a cylindrical member substantially coaxial with said cathode and having a lengthwise outward bulge at one portion of the periphery thereof to increase, at that portion, the distance between the plate and the cathode, and a conducting post disposed lengthwise of the wires of the helix to support the same, said post being located in the portion of inter-electrode space adjacent to said outer anode bulge to secure substantially the same insulating clearances throughout the entire inter-electrode space of the tube. 25 30 35

In testimony whereof, I have hereunto subscribed my name this 24th day of June, 1926. 40

SAMUEL M. KINTNER
